B. R. WEBSTER

ELECTRICAL CONDENSER

Filed April 28, 1924

UNITED STATES PATENT OFFICE.

BESTER R. WEBSTER, OF CHICAGO, ILLINOIS, ASSIGNOR TO RELIANCE DIE & STAMPING COMPANY, OF CHICAGO, ILLINOIS, A CORPORATION OF ILLINOIS.

ELECTRICAL CONDENSER.

Application filed April 28, 1924. Serial No. 709,513.

My invention relates to electric condensers, the condenser of my invention being of particular service when employed in systems of wireless communication, though the condenser of my invention is not to be limited to any particular use thereof.

The invention relates particularly to those condensers each of whose sides is composed of a group of electrically connected leaves that are alternated with the leaves of the group composing the other side, means being afforded whereby less than the complete number of the condenser leaves of one side may be adjustable with respect to the remaining leaves of this side and with respect to the other side of the condenser. In a condenser of this class, the adjustable condenser side had most of its leaves mounted upon a quill shaft and a minor portion of its leaves upon a solid shaft within the quill shaft. The solid shaft had one bearing upon the exterior of the quill-shaft and was also journaled in the bore of the quill shaft. The quill-shaft was journaled in a surrounding bearing and also directly upon the solid shaft. The electrical and mechanical unity of the condenser plates carried by these shafts depended upon the accuracy of their fit, and the snugness of their fit prevented independence of their adjusting movements, the adjusting movement of one shaft frequently causing an undesired adjusting movement of the other.

In practicing my invention, a sleeve or nut is carried by the solid or inner shaft and serves as a bearing for the adjacent end of the quill shaft that also, in turn, acts as a bearing for the nut, whereby each shaft rotatably supports the other very closely adjacent the leaf carried by the inner shaft to eliminate the danger of short circuiting the condenser sides at this part of the condenser.

The invention will be more fully explained in connection with the accompanying drawing in which:

Fig. 1 is a side view of a condenser constructed in accordance with the preferred embodiment of the invention, front end portions of the two shafts being broken away; Fig. 2 is an axial sectional view;

Fig. 3 is a sectional view on line 3-3 of Fig. 1; and

Fig. 4 is an enlarged view of a part of the structure as it appears in Fig. 2.

55

The condenser illustrated includes two mounting plates 1 and 2 of insulating material which are assembled upon threaded metallic rods 3 by means of nuts 4. These mounting plates are suitably assembled with the mounting board or panel 5. One of the condenser sides includes a group of metallic leaves 6 through which the rods 3 pass and which are electrically connected by means of metallic sleeves 7 having slots which receive 65 said leaves 6. The other condenser side includes a group of metallic leaves 8, these leaves being alternated with the leaves of the first group, as illustrated. The condenser side 8 is mounted to be adjustable with respect to the other condenser side, the adjustable group being rotatably supported upon the insulating mounting plates 1 and 2.

70

The support for the group of leaves 8 which is rotatively mounted in the plates 1 and 2 is inclusive of a rotatable sleeve or hollow shaft 9 having a flanged knob 10 upon the outer end thereof, this knob being provided with scale marks upon its periphery, and being rotatable in front of suitable 80 marking upon panel 5 whereby the extent of rotative movement of the rotatable condenser side carried thereby may readily be determined. The leaves 8 are spaced apart by washers 8'. The set screw 9' carried by 85 the collar 9² prevents the hollow or quill shaft 9 from being moved forwardly longitudinally of its axis. The quill shaft is prevented from moving rearwardly toward the plate 1 as will appear.

90

Shaft 11 is journaled in the bore of the hollow shaft or sleeve 9. Its front end projects beyond the front of the knob 10 and carries a knob 12 that bears suitable scale marks upon its periphery to cooperate with suitable marking upon the knob 10 in defining the extent of the refining adjustment of the inner shaft with respect to the hollow shaft.

95

The condenser plate 13 belongs to the adjustable condenser side and supplements the plates 8. It is mounted upon the shaft 11,

100

that passes therethrough, by means of nuts 14' 15 threaded upon this shaft and between which this supplemental condenser plate is clamped so as to turn with this shaft. A washer 16 is pressed in frictional contact with the shoulder upon the adjacent end of the quill shaft 9 by the adjacent nut or sleeve 15. This washer is formed with a tail 17 which engages rod 17' whereby the washer is held from rotation, and serves as a brake to prevent either shaft 9 or 11 from being turned by the other. The washer also serves to maintain electrical unity between the two relatively adjustable parts of the rotatable condenser side and to prevent rearward movement of the quill shaft 9. The inner shaft 11 is extended rearwardly beyond the outer shaft 9 and projects through and beyond the rear mounting plate 1 in which it may be journaled, if desired.

Friction between the stationary washer 16 and the adjacent nut 15, and adjacent collar 8' may be maintained in any suitable way. I have indicated a leaf spring 18 for this purpose, this spring being anchored at one end, to the plate 1 by the screw 19 and being adjustably pressed at its other end upon the rear end of shaft 11 by an adjusting screw 20 entering the plate 1.

The journal 21 for the front end of the 30 quill shaft may be externally conical to fit a conical opening in the plate 2.

It is obvious that changes may be made without departing from my invention.

Having thus described my invention, I 25 claim:

In an electric condenser, the combination with one group of electrically connected leaves constituting one condenser side; of a second group of electrically connected 40 leaves alternated with the leaves of the first group and constituting the other condenser side; a rotatable quill-shaft carrying a portion of the leaves of one group; an inner shaft passing through the 45 bore of the quill-shaft and carrying a leaf of the latter group; a sleeve assembled with the inner shaft and receiving and turning upon one end of the quill-shaft which has a cylindrical end portion that turns upon and 50 within this sleeve, one end of said inner shaft passing through and projecting beyond said sleeve; a bearing for said projecting end of the inner shaft; and a bearing for the quill-shaft.

In witness whereof, I hereunto subscribe my name.

BESTER R. WEBSTER.
